UNITED STATES PATENT OFFICE

2,459,355

OARLOCK EXTENSION

Max W. Areaux, Paw Paw, Mich.

Application December 5, 1946, Serial No. 714,333

10 Claims. (Cl. 9—26)

1

This invention relates to improvements in an oarlock extension.

The principal objects of this invention are:

First, to provide a device which may be easily carried and installed by fishermen or sportsmen for elevating the oars of rowboats so that the oars may be operated without bumping the knees of the rower.

Second, to provide an oarlock extension for elevating the oars above the thwarts of a rowboat, which extensions may be inexpensively manufactured.

Third, to provide an extension for raising the oars above the thwarts of a boat which may be conveniently locked to the oars or to the thwart of the boat to prevent loss of the extension in the water.

Other objects and advantages pertaining to the details and economies of this invention will be apparent from the following description and claims.

The drawings, of which there is one sheet, illustrate two practical forms of my rowing aid.

Fig. 1 is a fragmentary elevational view partially in vertical cross section of one form of my rowing aid in operative position between the oar and thwart of a rowboat.

Fig. 2 is a perspective view of a pair of the extensions illustrated in Fig. 1 hooked together for convenient carrying as in the tackle box of a fisherman.

Fig. 3 is an elevational view of a modified form of my device.

My rowing aid is designed particularly for the use of fishermen and sportsmen who are in the habit of renting boats from public boat liveries. It is a general characteristic of public boats that the boats are constructed with a minimum of material resulting in the thwarts and oarlocks being positioned no further from the bottom of the boat than is absolutely necessary to provide a boat which will float. As a result fishermen renting these boats find that the oars are constantly bumping against their knees and that extended rowing of the boats as while troll fishing is very uncomfortable. My rowing aid consists of a pair of extensions which will fit into the oarlock sockets of a boat and support the oarlocks and oars in an elevated position above the sides of the boat. With this aid the rower is able to assume a more natural and comfortable position in the boat and still operate the oars without constantly bumping his knees.

In the drawings, the reference numeral 1 indicates the side or thwart of a boat which is pro-

vided with an oarlock socket 2 secured to the thwart by means of the socket plates 3. My rowing aid which normally will be purchased and used in pairs is indicated at 4 and consists of a generally cylindrical body portion defining a cylindrical recess 5 in one end thereof and having a stud portion 6 formed on the opposite end thereof coaxial with the recess 5. The stud 6 is of the same general dimension as the studs on standard oarlocks so as to fit easily and rotatably within the socket members 2 of most rowboats. The lower end of the stud is flattened and apertured as at 7.

The upper end of the body of the rowing aid 15 is provided with a pair of ears 8 which define apertures 9 arranged to engage the spring clips 10 secured to the ends of a coupling chain or cable 11. The entire rowing aid with the exception of the spring clips and chain is conveniently 20 and inexpensively formed as by casting a number of the devices in a single mold and tumbling the castings to remove burrs and rough edges.

The recess 5 is of such a length and diameter as to freely and rotatably receive the stud portion 12 of a standard oarlock 13, the particular oarlock illustrated being provided with horns 14 supporting a pin 15 extending through the center of the oar 16.

When in use the stud of the rowing aid is positioned in the socket of the boat and one end of the chain 11 passed between the horns of the oarlock and snapped on one of the ears 8 as illustrated to connect the aid to the oar and prevent the loss of the rowing aid should it stick to the oarlock when the oar is removed from the thwart of the boat. For carrying a pair of the rowing aids the stud of one aid may be positioned in the recess of the other aid and the chain of one aid clipped to the apertured stud of the other to hold 40 the two together as illustrated in Fig. 2. In this position the rowing aids are conventionally held together and may be easily carried in the tackle box of a fisherman.

A modified form of my rowing aid is illustrated 45 in Fig. 3 and consists of a body 4A defining a recess 5A and having a stud 6A formed on the opposite end thereof from the recess. The body 4A is not provided with ears as in the first form of my rowing aid but the apertured lower end 7A of the stud is provided with a lock chain 11A having a cross link 17 secured to the bottom thereof. This form of rowing aid is secured in the socket of the boat by tilting the arms of the cross link 17 into vertical position and dropping them 50 through the socket ahead of the stud 6A so that

the arms of the cross link will hang in a generally horizontal position on the underside of the socket and prevent accidental displacement of the rowing aid from the socket. Thus this form of rowing aid is secured to the thwart of the boat rather than to the oars as in the first form illustrated. Otherwise both forms of my rowing aid operate in the same manner to elevate the oars of the boat above the knees of the user.

I have found that a rowing aid having a body between 4 and 6 inches long is adequate to elevate the oars above the knees of the user when used in the general style of boats found in public boat liveries. I have described two forms of my rowing aid which are both inexpensive and highly practical so that others may reproduce the same without further disclosure.

Having thus described my invention, what I claim as new and desire to secure by Letters Patent, is:

1. A rowing aid in combination with a boat having an oar, oarlock and oarlock socket comprising an extension member having a body portion defining an auxiliary socket adapted to rotatably receive the stud of said oarlock, an auxiliary stud on said body portion and at the opposite end thereof from said auxiliary socket adapted to be rotatably received in said oarlock socket, ears formed on the sides of said body portion and defining apertures, and a chain adapted to be passed between the horns of said oarlock and having spring clips on the ends thereof engageable in said apertures, the ends of said auxiliary stud defining another aperture.

2. A rowing aid in combination with a boat having an oar, oarlock and oarlock socket comprising an extension member having a body portion defining an auxiliary socket adapted to rotatably receive the stud of said oarlock, an auxiliary stud on said body portion and at the opposite end thereof from said auxiliary socket adapted to be rotatably received in said oarlock socket, ears formed on the sides of said body portion and defining apertures, and a chain adapted to be passed between the horns of said oarlock and having hooks on the ends thereof engageable in said apertures.

3. A rowing aid in combination with a boat having an oar, oarlock and oarlock socket comprising an extension member having a body portion defining an auxiliary socket adapted to rotatably receive the stud of said oarlock, an auxiliary stud on said body portion and at the opposite end thereof from said auxiliary socket adapted to be rotatably received in said oarlock socket, an ear formed on the side of said body portion and defining an aperture, and a chain having spring clips on each end thereof, said clips being removably secured in said apertures with said chain passing between the horns of said oarlock for retaining said extension member on said oarlock.

4. A rowing aid comprising a pair of extension members having body portions defining cylindrical recesses adapted to receive the studs of oarlocks, auxiliary studs formed on the other ends of said body portions from said recesses and adapted to nestingly fit in said recesses and in the sockets of a rowboat, said auxiliary studs defining apertures at the lower ends thereof, apertured ears formed on the sides of said body portions, and a pair of chain members having spring clips on each end thereof adapted to be engaged through said apertures in said ears and said auxiliary studs to hold said body portions together in one position and to hold said body portions individually to oarlocks in another position.

5. A rowing aid comprising a pair of extension members having body portions defining cylindrical recesses adapted to receive the studs of oarlocks, auxiliary studs formed on the other ends of said body portions from said recesses and adapted to nestingly fit in said recesses and in the sockets of a rowboat, said auxiliary studs defining apertures at the lower ends thereof, apertured ears formed on the sides of said body portions, and a pair of chain members having hooks on each end thereof adapted to be engaged through said apertures in said ears and said auxiliary studs to hold said body portions together in one position and to hold said body portions individually to oarlocks in another position.

6. A rowing aid comprising a body member defining a central recess in one end thereof adapted to receive the stud of an oarlock, an auxiliary stud formed on the other end of said body portion and coaxial with said recess, the end of said stud being flattened and defining an aperture, a lock chain having one end secured in said aperture, and a cross link having oppositely extending arms secured to the other end of said chain.

7. A rowing aid comprising a body member defining a central recess in one end thereof adapted to receive the stud of an oarlock, an auxiliary stud formed on the other end of said body portion and coaxial with said recess, the end of said stud defining an aperture, a lock chain having one end secured in said aperture, and a cross link having oppositely extending arms secured to the other end of said chain.

8. A rowing aid comprising a body member defining a central recess adapted to receive the stud portion of an oarlock, an auxiliary stud formed on the opposite end of said body from said recess and adapted to fit within the oarlock socket of a boat, the lower end of said auxiliary stud being flattened and defining an aperture, and a securing chain connected to said body, said stud being axially aligned with said recess.

9. A rowing aid comprising a body member defining a central recess adapted to receive the stud portion of an oarlock, and an auxiliary stud formed on the opposite end of said body from said recess and adapted to fit within the oarlock socket of a boat, the lower end of said auxiliary stud being flattened and defining an aperture, said stud being axially aligned with said recess.

10. A rowing aid comprising a body member defining a central recess adapted to receive the stud portion of an oarlock, and an auxiliary stud formed on the opposite end of said body from said recess and adapted to fit within the oarlock socket of a boat, said stud being axially aligned with said recess.
